UNITED STATES PATENT OFFICE.

JOSIAH BRADLEY, OF BROOKLYN, NEW YORK.

RETORT SLICING DEVICE.

Application filed May 26, 1924. Serial No. 715,774.

To all whom it may concern:

Be it known that I, JOSIAH BRADLEY, a citizen of the United States, residing in the borough of Brooklyn, county of Kings, city and State of New York, have invented an Improvement in Retort Slicing Devices, of which the following is a specification.

My present invention relates to an improvement in apparatus for extracting the volatiles from coal, lignite and similar materials and more particularly to that type of apparatus of this class designed to operate continuously at so-called low temperature and in which the heat for extracting the volatiles is obtained by burning a portion of the charge at the bottom of the retort. The apparatus made in accordance with my invention comprises novel features in the construction of the devices for supplying the material to be treated to the retort, in the devices for regularly slicing the material above the grate, to the devices for discharging the coke and other residue, as well as to the devices for condensing the gases and volatiles as conveyed away from the retort. In the present case, however, the invention will be restricted to the apparatus for regularly slicing and ejecting the material immediately above the grate, and the means for operating the same.

I am aware that heretofore various devices have been employed for slicing and ejecting the material above the grate in the type of apparatus to which my invention relates. In this type of apparatus there is a tendency in the operation thereof for the burning charge at the bottom of the retort to become caked and when this occurs the difficulties of properly slicing and ejecting the material are greatly increased. The object of my invention is to overcome this difficulty and to provide a slicer device which in its action tends to break up any caking tendency of the burning charge at the bottom thereof so that a predetermined quantity of the burning charge may be removed with each slicing operation. To this end in carrying out the invention the slicer device is an oscillating apparatus which swings from a line extending directly across the retort an appreciable distance below the same so that the slicer bar travels in the arc of a circle tending to raise the charge within the retort and thus prevent the same from becoming caked or wedged and making the slicing operation uncertain. Furthermore

in carrying out the invention the slicer bar as well as the grate and the lower sections of the retort are provided with suitable passages for a circulating medium to prevent the same from becoming overheated and thus prolonging the life of these parts of the apparatus. Suitable devices are also employed for operating the slicer bar and other parts of the apparatus, as will be hereinafter more particularly described.

In the drawing:

Fig. 1 is a sectional elevation illustrating more or less diagrammatically an apparatus made in accordance with my present invention, the section being taken on line 1—1, Fig. 2.

Fig. 2 is a similar view taken on line 2—2, Fig. 1.

Fig. 3 is a transverse section of a portion 75 of the grate bar, and

Fig. 4 is a transverse section of a portion of the slicer bar.

In carrying out the invention and as is customary, the apparatus may be mounted 80 on a suitable foundation 10. Rising from the foundation are suitably spaced supports or standards 11 and 12 which may be made of brick work, as illustrated, or in any other similar manner. At the top of these supports a grate 13 is mounted. As illustrated this may be secured in position by end plates 14 and tie-bolts 15 or otherwise. Each grate bar is preferably a hollow structure providing a chamber 16 and fitted with inlet and outlet pipes or connections 17 and 18, by which water or any other cooling medium from a suitable source and by any means may be circulated through the grate. Also as indicated in the drawing the upper surface of the grate is preferably made on the 85 are of a circle.

Above the grate there is a retort 19. This is preferably a vertical retort made of brick work or otherwise and as illustrated 100 is rectangular in plan, although, as will be understood the particular configuration of the retort forms no part of my present invention. At the lower end of the retort there are bosh bars 20 fitted with suitable pipes 21 and 22 for the supply of water or any other suitable cooling medium for circulation through these bosh bars. The retort, as illustrated, is supported upon beams 23 carried at the upper ends of the standards 24 and 25, although as will be 105 understood the particular manner in which 110

the retort is supported forms no part of the invention. Also as illustrated the retort is provided with a cover and the retort as well as the grate and the parts supporting and cooperating with the same are enclosed in a suitable housing 27. This housing may be made of sheet metal or other similar and suitable material and may include an auxiliary section 28 for enclosing a separate compartment for a motor driven device, as hereinafter described. Furthermore, as illustrated in Fig. 1 of the drawing, in suitable positions in the walls of the retort I may provide apertures 29 for the insertion of pyrometers or other devices for ascertaining the temperatures and working conditions at different sections in the interior of the retort.

Cooperating with the grate there is a slicer bar indicated at 30. At the ends thereof this slicer bar is suitably connected to rods 31 and 32. These rods are arranged in pairs as illustrated in the drawing and one pair is employed at one end of the grate and the other pair at the opposite end of the grate. At their lower ends the rods 31 are secured in a block 33 which is connected to a shaft 34 journaled in suitable bearings 35 preferably located in the foundation as illustrated. In a similar manner the lower ends of the rods 32 are fixed in a block 36 which is mounted on a shaft 37 journaled in bearings 38 also suitably secured in the base or foundation of the apparatus. The centers of the shafts 34 and 37 are in a line which extends diametrically through the longitudinal center of the retort as indicated in the drawings and the slicer bar is connected at the upper ends of these rods 31 and 32 in such a manner as to travel over the grate bar for effecting the slicing operation. The slicer bar is operated as illustrated by a motor driven apparatus. The rods 31 and 32 for example may be fitted in suitable positions with blocks 39 which are pivotally connected to chains 40. These chains 40 pass over sprockets 41 and 42. The sprockets 41 are fixed on a suitably journaled shaft 43 and the sprockets 42 are fixed on a suitably journaled shaft 44. Also mounted on the shaft 44 there is a gear 45. This gear 45 meshes with a worm 46 on a shaft 47, the shaft 47 being suitably coupled to the shaft of a motor 48. The motor 48 is mounted on a base 49 and this motor, together with the shaft 44 and the parts carried thereby, are housed in a separate compartment, to which reference has hereinbefore been made, by the auxiliary housing wall 28. It will be understood, of course, that the motor may be located exteriorly of the housing wall but as illustrated is shown within the housing wall. The motor may be operated in opposite directions by any suitable means to turn the shaft 44 first in one direction to correspond-

ingly move the chains 40 and swing the slicer bar in one direction and then the motor may be reversed, causing the shaft 44 to turn in the opposite direction and the chains 40 to move in the reverse direction thereby swinging the slicer bar back to its starting point which may be considered an initial position for the same. The slicer bar is also preferably water-cooled and to this end the same may be fitted with pipe connections 50 and 51 for the intake and discharge of the cooling medium which may be supplied thereto from any suitable source, it being understood, of course, that a portion at least of these pipe connections for the cooling medium in this instance must be flexible to permit of a swinging movement of the slicer bar. It will also now be understood that the slicer bar travels on the arc of a circle concentrically with the upper face 83 of the grate and in so doing will raise or tend to raise to some extent the lower portion of the charge within the retort thereby breaking up this portion of the charge should the same become caked and so insuring the delivery of a predetermined quantity of the residue with each slicing operation.

At the upper end or on top of the retort there is a hopper 52 for the reception of the coal, lignite or other material from which the volatiles are to be extracted in the operation of the apparatus. The lower end of the hopper is provided with a chute or inclined walls 53 leading to a casing 54 in which a revoluble drum 55 is mounted. In a suitable position in the walls of this drum there is an opening 56 which in the revolution of the drum registers with the mouth defined by the inner ends of the walls of the chute to admit the coal, lignite or other material to the interior of the drum and when the drum is in the oppositely disposed position this opening 56 therein registers with an opening 57 in the top wall 58 of the retort in order that the drum may discharge its contents into the retort without opening the same to the atmosphere. The drum is journaled in bearings 59 and 60 provided therefor in the walls supporting the hopper and is turned by a shaft 61. This shaft carries a gear 62 meshing with a worm 63 on a shaft 64 which is suitably coupled to the shaft of a motor 65. As illustrated the motor 65 is supported upon a bracket 66 also enclosed within a portion of the housing. This motor 65 is suitably controlled to operate the drum in such a manner as to at all times in the operation of the apparatus maintain the charge within the retort at a predetermined height which is adjacent the upper end of the retort so that the retort is constantly filled to approximately its maximum capacity.

The devices employed for discharging the coke and other residue are similar to those

hereinbefore described for the admission of the material to the retort. At both ends of the grate bars the same are fitted with chutes 67. These chutes 67 lead to a discharge cylinder 68 in which a casing 69 is mounted. Within the casing 69 there is a drum 70. In the walls of the drum 70 there is an opening which when the drum is in a predetermined position registers with the ends of the chute and the corresponding portions of the casing, and when the drum is in the diametrically opposite position opens into the discharge cylinder 68 so as to permit the drum to automatically discharge itself. The drum 70 is mounted on a shaft 71. On this shaft there is a gear 72 meshing with a worm 73 carried by a shaft 74. The shaft 74 is suitably coupled to the shaft of a motor 75 mounted on the platform or other support 76. This motor 75 like the motor 65 may be suitably operated to intermittently discharge the coke and residue as the same is sliced from the grate bars and caused by the chutes 67 which act as a hopper to descend to the drum to be regularly discharged thereby through the discharge pipe 88 to a pit 77 or otherwise. These devices for the admission of the material to be treated and the discharge of the coke and other residue are herein illustrated more or less diagrammatically. In devices for this purpose as heretofore constructed difficulty has been experienced in preventing the same from becoming clogged with tar and pitch and similar substances. These parts, however, as included in my improved apparatus are self-cleaning and are more particularly described in a separate application made to cover the same.

The volatiles and gases are conveyed from the retort through an opening 78 made for this purpose in the top thereof and are carried through a pipe 79 to a blower or exhaust 80 by means of which a partial vacuum is maintained within the retort. This blower is driven by a motor 81 mounted on a suitable bracket 82 or otherwise and supported upon the housing of the apparatus. The discharge end of the blower 80 is connected by a pipe line 83 to the bottom of a condenser 84 and the discharge from the condenser leads from the upper end thereof by way of a pipe line 85 to a scrubber 86, there being a branch pipe 87 leading from the pipe line 85 to the scrubber 86 and in the branch pipe 87 there is a valve 88. The pipe line 85 is continued as indicated at 89 and fitted with a valve 90 so as to lead to the lower end of a stack 91. It will be understood of course that when it is desired to obtain only the heavy volatiles the gases as the same leave the condenser are conveyed by the pipe lines 85 and 89 directly to the stack 91, the valve 90 being open and the valve 88 being closed for this purpose, whereas if it is desired to

obtain the lighter volatiles the valve 90 may be closed and the valve 88 open so that the gases as the same come from the condenser will first pass to the scrubber 86. The gases as will be understood may be refined to any desired extent and as indicated more or less diagrammatically the discharge from the scrubber may be connected by a pipe line 87 to the bottom of the stack.

In the use of the foregoing apparatus the charge in the retort is suitably lighted at the lower end thereof to produce the necessary heat for the extraction of the volatiles from the materials under treatment, the successive portions of the charge as the same descends through the retort becoming ignited after the volatiles have been extracted therefrom to maintain the source of the heat required. The operation of the supply device, the slicer bar and the discharge devices may all be suitably regulated to maintain this heat at the most advantageous temperature for any particular material under treatment, varying from 350° to approximately 800° Fahrenheit. This control may be effected manually by the attendant operating the motors at the necessary periods to cause a continuous operation of the apparatus, or the same may be effected by a thermocontrol or other device, depending of course upon the heat within the retort so that the motors operating the several parts may be operated when necessary to accomplish this purpose. The control of the apparatus, however, forms no part of my present invention which, as hereinbefore stated, is restricted to the construction of the grate, slicer device, the parts associated therewith and apparatus for operating the same.

In the use of the apparatus as hereinbefore described, the material to be treated will be coal in one form or another in a great majority of installations, and when coal is the material treated the heat for the extraction of the volatiles therefrom is preferably generated as hereinbefore stated by burning the charge or a portion thereof in the lower section of the retort. It will be understood, however, that in the extraction of volatiles from other materials, such for example as lignites, shales and the like, which are less combustible than the coal, it will be necessary to utilize an additional apparatus which may be of any type for externally generating and applying the necessary heat for the extraction of the volatiles, and in some instances it may also be necessary to generate the heat externally in the extraction of volatiles from coal, and it will be understood that the heat may be so generated and applied without departing from the nature and spirit of my invention.

I claim as my invention:

1. In a retort slicing apparatus, a grate beneath the open lower end of a retort, and

upon which the lower portion of the material in the retort rests, and an oscillating slicer bar adapted to move over the said grate to remove a portion of the material above the grate with each oscillation of the slicer bar.

2. In a retort slicing apparatus, a grate at the lower open end of a retort, and upon which material in the retort rests, an oscillating slicer bar, and means for actuating the slicer bar to swing the same over the grate to remove a portion of the material from the retort.

3. In a retort slicing apparatus, a grate having a curved upper surface extending across the lower open end of a retort, and upon which material in the retort is adapted to rest, and an oscillating slicer bar adapted to move in close proximity over the curved surface of the grate bar to move a portion of the material from the retort.

4. In a retort slicing apparatus, a grate having a curved upper surface extending beneath the lower open end of a retort, and adapted to support material within the retort, an oscillating slicer bar, and means for swinging the slicer bar to and fro over the curved surface of the grate to remove a portion of the material in the retort each time the slicer bar is actuated.

5. In a retort slicing apparatus, a hollow grate extending across the lower open end of a retort, and adapted to support the material in the retort, an oscillating slicer bar, and means for oscillating the slicer bar over the grate to remove a portion of the material within the retort.

6. In a retort slicing apparatus, a grate extending across an open lower end of a retort, and adapted to support the material within the retort, a hollow slicer bar, and means for oscillating this hollow slicer bar

over the surface of the grate to remove a portion of the material in the lower end of the retort.

45

7. In a retort slicing apparatus, a hollow grate adapted to extend across the lower open end of a retort, and to support material within the retort, a hollow slicer bar, and means for oscillating the hollow slicer bar over the upper surface of the grate to remove a portion of the material in the lower part of the retort.

8. In a retort slicing apparatus, a hollow grate having a curved upper surface, adapted to extend across the lower open end of a retort, and to support material within the retort, a hollow slicer bar, devices for passing a circulating medium through the said hollow grate and the slicer bar, and means for oscillating the slicer bar across the curved surface of the grate to remove a portion of the material in the lower end of the retort with each operation of the slicer bar.

55 9. In a retort slicing apparatus, a grate, a slicer bar, a rocker shaft, means for connecting the rocker shaft to the slicer bar, and devices for swinging the said means to oscillate the slicer bar over the upper surface of the grate to remove the portion of the material in the lower end of the retort.

10. In a retort slicing apparatus, a grate extending across the lower open end of a retort, and adapted to support material therein, a slicer bar, a rocker shaft, rods connecting the slicer bar and rocker shaft, and means for swinging the said rods on the rocker shaft to thereby oscillate the slicer bar across the upper surface of the grate to remove a portion of the material from the lower end of the retort.

75 Signed by me this 21st day of May, 1924.

JOSIAH BRADLEY.
